(57) CLAIM

The ornamental design for a combined sofa and privacy screen, as shown and described.

DESCRIPTION

FIG. 1 is a front perspective view of a first embodiment of the combined sofa and privacy screen embodying the new design;

FIG. 2 is a side view thereof;

FIG. 3 is a front view thereof;

FIG. 4 is a rear view thereof;

FIG. 5 is a top view thereof;

FIG. 6 is a bottom view thereof;

FIG. 7 is front perspective view of a second embodiment of the combined sofa and privacy screen embodying the new design;

FIG. 8 is a side view thereof;

FIG. 9 is a front view thereof;

FIG. 10 is a rear view thereof;

FIG. 11 is top view thereof; and,

FIG. 12 is a bottom view thereof.

FIGS. 1-12 show portions of the combined sofa and privacy screen in broken lines. The portions of the combined sofa and privacy screen shown in broken lines form no part of the claimed design. Stipple shading is added to convey surface contouring; the stipple shading is not to be understood as conveying a particular surface finish.
